UNITED STATES PATENT OFFICE.

WILLIAM B. BARLEY, OF ROCHESTER, NEW YORK.

DISHWASHING MACHINE.

Application filed October 14, 1922. Serial No. 594,577.

My invention relates to a dish washing machine, more particularly to the general type of machine involving a stationary water containing tub, and a dish receptacle or basket frame that is movable back and forth through the water in the tub, and it has for its purpose to provide mechanism which can be readily controlled, and enables performing a washing operation in less time and more efficiently than heretofore.

More specifically, a principal purpose of the improvement is to provide a mechanism for readily lowering or elevating a basket of dishes into or out of the tub, as well as a simple, economical, and easily controlled mechanism for retaining the basket in its uppermost position when out of the tub.

Another object of the improvement is to afford a convenient and practical mechanism for guiding a dish receptacle properly as it is lowered into the tub, so as to prevent its coming in contact with any obstruction and to insure positioning it accurately on the movable frame.

A further purpose of the invention is to afford a motor driven mechanism involving gearing which includes a locking means that can be disconnected so as to release the movable frame from the motor drive and permit it to be operated by hand in an emergency, such disconnecting mechanism involving but few parts and being exceedingly simple in its construction.

The invention also includes certain other features of improvement and advantages, all of which will appear clearly from the following description in conjunction with the accompanying drawings, the novel characteristics being pointed out in the claims following the specification.

In the drawings:

Figure 1 is a side view of a machine incorporating a preferred embodiment of my invention, and showing a portion of the tub broken away, the dish receptacle appearing in elevated position;

Figure 2 is a plan view of the same with parts broken away;

Figure 3 is a transverse section with the dish receptacle in elevated position;

Figure 4 is a side elevation illustrating the position of the parts when operated by motor power;

Figure 5 is a similar view, showing the motor drive disconnected, to permit hand operation of the machine;

Figure 6 is an enlarged sectional view of the means for locking the motor driven crank rod with the lever which controls the machine, the parts appearing in normal position;

Figure 7 is a similar view, with the crank rod and lever disconnected to permit a hand operation, and

Figure 8 is a detail view of a portion of the driving mechanism.

In the construction illustrated, which is intended merely as an example of various possible applications of the improvements, 1 designates a stationary tub which may include several compartments for washing and rinsing, as usual in this class of machinery, and arranged within the tub for oscillatory back and forth movement is a supporting frame in which the dish basket or receptacle 73 is placed. The oscillatory supporting frame includes a bottom 2 and suitable hangers which are pivoted and swing about the centers 3, the frame being oscillated by mechanism that will be described presently. 80

In order to insure properly positioning a dish basket on the bottom of the frame, and prevent its coming in contact with any obstruction as it enters the tub, I employ a guiding means that extends from the top of the tub downwardly and inwardly toward the frame, and acts to engage the bottom of the dish basket as it is lowered and direct it to a central position on the bottom of the frame. This guiding means may be of 90 varied form, but preferably I employ a series of relatively slidable or telescopic connections between the bottom of the frame and the top of the tub. This may be accomplished by rods 4, pivotally connected 95 to the supports 5, and sliding in tubes 6 which in turn are pivoted at 7 to the bottom of the oscillatory frame. Thus, the telescopic members 4 and 6 afford an inclined 100 guide against which the dish basket engages as it is lowered into the tub. The same purpose can be accomplished by any relatively sliding members connected between the tub and the bottom of the movable frame, or the guide may be otherwise constructed, not necessarily including telescopic or relatively sliding members so long as it has the necessary inclination downwardly and inwardly with reference to the movable dish receptacle 105 frame and acts to direct a dish basket to proper position on the frame.

A well known and conventional form of

dish basket or container is illustrated at 8, and includes upstanding handle portions 9 by which it can be lifted out of the tub, and in order to conveniently elevate or lower the basket, or move it lengthwise of the tub from one compartment to the other while loaded with dishes, I employ the mechanism that will now be described.

10 designates a track suitably arranged above the tub, and mounted for travel on said track is a carrier that includes a housing 11 connected to a bracket 12 which has journaled thereon wheels 13 travelling on the track 10, and a roller 14 which engages 15 the underside of the stationary support 15 and is prevented against downward movement or tilting by a guard 16.

Journalled in the housing 11 is an elevating device preferably in the form of a conical drum having a handle 17 by which it is rotated. Said conical drum is provided with a spirally arranged groove 18 which terminates at the small end of the roll in a cut-away or deepened portion 19, thereby affording 25 a retaining portion 20 which is of reduced diameter, as appears in Figure 3, and is so arranged that its entire cable engaging surface is eccentric with reference to the rotary axis of the elevating device. 21 designates a cable, one end of which is connected to the large end of the elevating drum while the opposite end is connected to a suitable rod 22 which is adapted to engage the handles 9 of the basket.

35 Assuming that the basket is in its lowermost position in the tub, when desired to elevate it, the rod 22 is lowered and engaged with the handles 9. The handle 17 is then turned, causing the cable 21 to wind upon the groove in the lifting drum until the uppermost position is reached. At this point, the cable 21 engages the reduced retaining portion 20 of the drum, the latter being then located below the rotary axis of 40 the roll, and the weight of the basket acts to hold the drum against further rotation and thus automatically locks itself in elevated position. To lower the basket, the handle 17 is turned in a reverse direction, 45 very slight pressure being needed to overcome the weight of the basket and elevate the retaining portion 20 to its highest point above the rotary axis of the roll, whereupon the weight of the basket carries it downwardly into the tub, and handle 17 being held sufficiently to prevent excessively fast motion of the basket.

When the dish basket is in its uppermost 50 position, as illustrated in Figures 1 and 3, the carrier can be moved lengthwise of the tub on the track 10, so as to bring the basket over any desired compartment, and to accomplish this movement readily, the housing 11 is provided with a handle 23 at one side thereof. It is desirable to hold the

housing 11, with the dish basket, in properly centered position above the selected compartment of the tub, and to this end I provide the support 15 with stationarily located spring-controlled locking pins 24 arranged to engage a cooperating recess 25 in the top of the housing 11. The action of the pin 24 is sufficient to hold the housing 11 against accidental displacement, although it can be disengaged by a slight pressure when it is desired to move it along the track.

In order to operate the basket frame, the latter has connected thereto a lever 26, pivoted on the bearing 3, connected with a motor drive by means that readily permits its being disconnected in case it is desired in an emergency to operate the basket frame by hand, as for instance, when the motor is disabled. To this end, the lever 26 is driven by a crank arm 27 which is likewise pivoted 35 on the bearing 3, concentrically with the lever 26. The crank arm 27 and lever 26 are independently movable, and adapted to be quickly connected for unitary movement when the motor is in operation. To effect 40 this, one of the parts, as for instance the lever 26, is slotted or cut away at its end as at 28 to receive a locking bolt 29, which is mounted on the other part or crank arm 27 and slidable thereon in a slot 30, while 31 45 designates a wing nut for tightening the bolt 29. By loosening the wing nut 31 and sliding the bolt endwise, the parts can be shifted from the position shown in Figure 4 to that shown in Figure 5, whereby the lever 26, 50 as well as the basket frame, is movable independently of the crank arm 27 and motor drive. To accomplish such hand operation, a hand lever 32 is provided which is normally in horizontal position, and can be thrown 55 to an upright position and moved into locked relation with the basket frame, as shown in Figure 5. For this purpose, the hand lever is slotted at 33, to engage pins 34 on the basket hanger 35, see Figure 5.

During the operation of the machine, the oscillatory frame is moved upwardly to its uppermost position under power, and swings downwardly under the impulse of gravity, thus having a tendency to run ahead of the 60 motor drive during each downward movement. To overcome the wearing effect of this lost motion on the driving parts, I employ the following mechanism. The crank arm 27, already described, is slotted at 36 to receive the crank 37, and the crank 37 is formed integral with gear 38, both said parts being preferably formed as part of an arbor 39. By making the gear 38 and crank 37 in one piece, I eliminate the possibility of loosening between these parts, which would take place if they were in two pieces and keyed or otherwise secured together. The arrangement described affords a much more durable, quiet, and practical means for driv- 65 70 75 80 85 90 95 100 105 110 115 120 125

ing the movable frame and does away with any mechanical disadvantage resulting from the irregular load due to the frame gravitating downwardly. The gear 38 is engaged by pinion 39^a mounted on arbor 40, which also carries pulley 41. A belt 42 engages pulley 41, and is driven from pulley 43, on the spindle 44 of motor 45.

While I have described the invention with reference to a preferred practical arrangement, the various features of improvement are susceptible of different other applications, and the structure shown may be modified without departing from the fundamental novelty of the invention, and this application is intended to cover any such departures or modifications coming within the intent of the improvements or the scope of the following claims.

20 I claim:

1. In a dish washing machine, the combination with a tub, of a supporting frame movable back and forth in the tub, and a guide arranged within the tub and comprising a pair of relatively slid-
25 able members connected to the tub and frame respectively.

2. In a dish washing machine, the combination with a tub, of a supporting frame movable back and forth in the tub, guiding means arranged within the tub and comprising a series of downwardly and inwardly inclined relatively slidable members, one end of each of which is connected near the top of the tub while the other end is connected at 35 the bottom of the frame.

3. In a motor driven dish washing machine, the combination with a movable frame, of a motor operated lever pivoted at its central part and connected at its lower 40 end to the frame, the lever having a recess in its upper end, a crank rod pivoted concentrically with the lever, and having a slot registering with said recess, and a locking bolt slidable in said slot into or out of the 45 recess in the lever.

In witness whereof, I have hereunto signed my name.

WILLIAM B. BARLEY.
